UNITED STATES PATENT OFFICE.

ARTHUR H. BRANDON, OF PEMBERVERILLE, OHIO.

FISHING-TOOL.

SPECIFICATION forming part of Letters Patent No. 772,864, dated October 18, 1904.

Application filed December 1, 1903. Serial No. 183,419. (No model.)

To all whom it may concern:

Be it known that I, ARTHUR H. BRANDON, a citizen of the United States, residing at Pemberville, in the county of Wood and State of Ohio, have invented certain new and useful Improvements in Fishing Tools; and I do hereby declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to improvements in fishing-tools for engaging and withdrawing broken or disabled valves from oil or other wells, and has particular reference to improvements in the invention for which application 20 for Letters Patent was filed by me on October 3, 1903, being Serial No. 175,565.

In the employment of the means heretofore devised for the recovery of broken or disabled valves from wells it has been necessary to first 25 withdraw the sucker-rod, which is usually several hundred feet long, from the well, remove the sucker-valve from the lower end thereof, secure the fishing-tool in its place, and then relower the sucker-rod with the fishing-tool attached into the well for the purpose 30 of engaging and withdrawing the valve.

The object of my present invention is to obviate the necessity for the several steps enumerated by providing simple and efficient means 35 whereby the fishing-tool is adapted to be suspended at all times from the lower end of the sucker-valve and to remain in the well therewith in inoperative position during the pumping operation and when desired to be released 40 from its inoperative position, so as to adapt it to engage the valve to be withdrawn, thus obviating the necessity of withdrawing the sucker-rod from the well and removing the sucker-valve in order to enable the fishing-tool to be 45 secured to said rod preparatory to recovering the disabled valve.

The invention is fully described and finally claimed in the following specification, of which the accompanying drawings form a part, in 50 which—

Figure 1 is a vertical sectional view of the

casing of a well, showing the usual sucker-rod and sucker-valve suspended therein, the inlet-valve in position below the same, and my invention in vertical longitudinal section suspended in inoperative position from the lower end of the sucker-valve. Fig. 2 is a similar view except that the sucker rod and valve are not shown, showing my fishing-tool in operative position and in engagement with the lower valve. Fig. 3 is a cross-sectional view of the tool-carrying member, taken on the dotted line $\alpha\alpha$ in Fig. 2; and Figs. 4 and 5 show a modification of the locking mechanism employed for retaining the fishing-tool in elevated position within its casing while being lowered into a well.

Referring to the drawings, A represents a sucker pipe or casing which has the inlet-valve B at its lower end and the sucker-rod C and sucker-valve D suspended therein, the said casing having its upper end threaded to a feed-pipe E of slightly-greater diameter than said casing, all of which are common to the class of wells in which my invention is adapted to be used.

My invention is shown in the drawings as comprising the elongated cylindrical member 1, which is made of suitable diameter to fit and reciprocate freely within the sucker-casing A and has its upper end internally threaded at 2 to engage the lower threaded end of the sucker-valve D, as shown in Fig. 1. The said cylindrical member 1 is adapted to form a housing for the engaging tool 3, which forms the subject of my said former application, the same comprising the enlarged portion, the longitudinally-slotted portion 5, having the annular flange or shoulder 5' at its free end, and the expanding tongue 6, the said tongue being adapted to normally extend below and have a limited longitudinal movement within the slotted portion 5 of said tool, as shown in Figs. 1 and 2. I do not confine myself, however, to this particular form of tool, as any suitable grappling means may be employed in connection with my invention.

The tool 3 is retained in different positions with relation to the member 1 by means of the locking-block 7, which rests and is transversely movable within a suitable opening provided through the casing of said member

- and has its upper inner edge beveled, the annular internal shoulder 8, which is adapted to coact with the enlarged portion 4 of said tool, and the transversely-movable pin 9, which is mounted in the lower portion of the casing 1 and adapted when in extended position to engage with the lower end of said tool and retain the same entirely inclosed within said member, as shown in Fig. 1. The sliding key 10 has a limited longitudinal movement within the dovetailed groove 10', provided in the side of the casing 1, by reason of the stop-pin 11 operating in the groove 11', and the movement of the pin 9 is controlled by the location of the key 10, which is provided with a notch 12 for receiving the end of said pin 9 when said key is in the elevated position shown in Fig. 2, thus unlocking and releasing the tool 3 from the position shown in Fig. 1.
- 20 The outer surface of the member 1 is provided with a series of longitudinal grooves 13, which terminate at their upper ends in the apertures 14, which lead to the interior of the member 1 and are in communication with the opening through the sucker-valve D, thus forming ways for the passage of oil or other fluid past the member 1 during the pumping operation should said member fit snugly in the casing A.
- 25 In the operation of my invention the member 1 is secured to the lower end of the sucker-valve D and lowered in the well therewith, the tool 3 being retained entirely within the same by reason of the locking-pin 9 engaging the lower end of said member, said pin being held in such position by the key 10, as shown in Fig. 1. This position of the tool 3 is maintained until the sucker-valve D and member 1 are lowered to the bottom of the sucker-casing A,
- 30 when the extended key 10 strikes the casing of the lower valve B and is forced up thereby, thus unlocking the pin 9 and permitting the tool 3 to drop within the member 1 until the enlarged portion 4 thereof comes in contact with the extended beveled edge of the locking-block 7. The pump is operated with the tool 3 suspended in this position until it is desired to withdraw the valve B, which is accomplished by first lifting the member 1, by means
- 35 of the sucker-rod C, until the locking-block 7 comes within the enlarged portion E of the pipe-casing, when it is forced out by the weight of the tool 3 against the beveled edge thereof, thus allowing said tool to drop until its enlarged portion 4 engages the shoulder 8, as shown in Fig. 2. The tool 3, which is now in position to adapt it to engage with the valve B, is relowered into the casing A, the block 7 being again forced in and locking the tool
- 40 against an independent upward movement. The tool is thus lowered until the extended tongue 6 passes through the opening in the lower valve-casing and strikes the ball therein, thus forcing said tongue up and expanding the flanged portion of said tool, so as to

engage the valve and enable it to be withdrawn.

It will be apparent that the locking-pin 9 or other suitable means is necessary in order to retain the tool 3 in inclosed position within the member 1 until the locking-block 7 has passed within the smaller casing A, after which time and during the pumping operation said tool is retained in inclosed position within said member by reason of the enlarged portion 4 thereof engaging the beveled edge of said block.

A modification of the means employed for retaining the engaging tool in inclosed position within its casing while it is being lowered into a well is shown in Figs. 4 and 5 of the drawings, in which *a* represents the sucker-pipe, *b* the enlarged portion of the pipe-casing, and *c* the cylindrical member for carrying the fishing-tool *g*. In this construction the locking-block *d* is adapted to be held in engagement with the enlarged portion of the fishing-tool *g* during the lowering operation by means of the split spring-ring *e*. As the member *c* is lowered and enters the smaller casing *a* the ring *e* engages the upper edge thereof, as shown, and is caused to remain stationary until the member *c* has been lowered sufficiently for it to spring within the peripheral groove or seat *f*, provided in said member for its reception, and thus be released from engagement with the edge of said casing.

It is obvious that such changes in the form, proportion, and minor details of construction of the parts as fairly fall within the scope of my invention may be made without departing from the spirit or sacrificing any of the advantages thereof.

Having thus described my invention, what I claim as new, and desire to secure by Letters Patent, is—

1. A fishing-tool, comprising a cylindrical member adapted to be suspended from and reciprocate with the sucker-valve of a pump, a valve-engaging tool carried by said member and adapted to be suspended therefrom, and means for retaining said tool inclosed within said member.

2. A fishing-tool comprising a hollow cylindrical member adapted to be movable with the sucker-valve of a pump, a valve-engaging tool carried within said member, means for retaining said tool in inoperative position, a member coacting with and adapted to control the movement of said means and release the same at a predetermined point.

3. A device of the class described, comprising a tubular member adapted to reciprocate with the sucker-valve of a pump, an engaging tool having a limited longitudinal movement within said member, means coacting with said tool for retaining it in operative or inoperative positions within said member, and locking means carried by said member for retain-

- ing said tool inclosed during the lowering operation of said member.
4. A fishing-tool holder, comprising a tubular member adapted to be suspended from the piston of a pump, a fishing-tool longitudinally movable in said member, a retaining-block coacting with said tool for the purpose described, and means for retaining said tool inclosed during the lowering operation of said member, substantially as described.
5. A fishing-tool holder, comprising a tubular member, a fishing-tool carried by said member, means for retaining said tool inclosed within said member while being lowered into a receiving-chamber, a block adapted to retain said tool in operative or inoperative positions and to release the same at a predetermined point in its movement, and a stop-shoulder provided in said member to limit the longitudinal movement of said tool, substantially as described.
6. In a device of the class described, a member adapted to be suspended within the casing of a well, an engaging tool carried by said member, and means carried by said member and coacting with said tool for retaining the same in operative or inoperative positions within said member.
7. In a device of the class described, a hollow tool-carrying member adapted to be suspended within a well, an object-engaging tool carried thereby and having a limited longitudinal movement therein, a member adapted to retain said tool in operative or inoperative positions with relation to said carrying member and to release said tool at a predetermined point, and means for locking said tool within said carrying member during the lowering operation, substantially as described.
8. In a device of the class described, a hollow member, an object-engaging tool carried thereby and having a limited longitudinal movement therein, means for locking said tool within said member and adapted to be released by coming in contact with a foreign object, and a member adapted to coact with and retain said tool in operative or inoperative positions and to be released by a movement of said member, substantially as described.
9. In a device of the class described, a tool-carrying member adapted to be suspended within the casing of a well, an object-engaging tool carried by and adapted to have a limited longitudinal movement therein, a member adapted to have engagement with said tool and be released therefrom at a predetermined point, and an element coacting with said engaging member and adapted to be released therefrom at a predetermined point in its descent by contact with an alining object, substantially as described.
10. In a device of the class described, a tool-carrying member adapted to be suspended within the casing of a well, a movable element therein provided with object-engaging means,

a member adapted to retain said tool in operative or inoperative positions with relation to said member and to be released at a predetermined point by a movement of said member, locking means longitudinally movable on said member and adapted to be released by contact with an alining object, and means for permitting the flow of fluid past said member, substantially as described.

11. The combination with the suction mechanism of a pump, of a tubular member suspended therefrom, an object-engaging tool operating in said member, means for retaining said tool in either suspended or inclosed positions, and locking means carried by said member adapted to retain said tool in inclosed position during the lowering of said member and to unlock by contact with an alining object.

12. In a device of the class described, the combination of a tool-carrying member having a locking-block in the casing thereof and a peripheral groove, a locking-ring coacting with said block and adapted when released therefrom to seat within said groove, an object-engaging tool carried by and having a limited longitudinal movement in said member and adapted to be retained in different positions therein by said locking-block, substantially as described.

13. In a device of the class described, a tool-carrying member adapted to be suspended from and operated by the pumping mechanism of a well, an object-engaging tool carried thereby and having its longitudinal movement limited, locking means mounted in and operated by a movement of said member and adapted to lock said tool in operative or inoperative positions with relation thereto, means comprising a longitudinally-slidable ring for locking and releasing said block at a desired point, and means for permitting the flow of fluid past said member, substantially as described.

14. In a device of the class described, a tool-carrying member, adapted to be secured to a piston and reciprocate therewith, an object-engaging tool carried thereby, a block, locking means for controlling the movements of said block, substantially as described.

15. In a device of the class described, a hollow member having a shoulder therein, an object-engaging tool movably mounted in said member and having its movement limited by said shoulder, and a lock for retaining said tool within said member adapted to be released after said member has been lowered in the casing of a well, substantially as described.

16. In a device of the class described, a hollow member having a shoulder therein and a groove on its external periphery, a transversely-movable block projecting within the casing of said member, an element longitudinally movable on said member adapted to coact with and retain said block in position and

to be released therefrom and seat within said groove at a predetermined point in the movement of said member, and an object-engaging tool carried within said member and adapted
5 to have its movements controlled by said block and shoulder, substantially as described.

In testimony whereof I have signed my name

to this specification in the presence of two subscribing witnesses.

ARTHUR H. BRANDON.
